(57) **CLAIM**

What is claimed is the ornamental design for a tablet computer, as shown and described herein.

DESCRIPTION

FIG. 1 is a top perspective view of a tablet computer showing the new design in a first embodiment;

FIG. 2 is a bottom perspective view thereof;

FIG. 3 is a top view thereof;

FIG. 4 is a bottom view thereof;

FIG. 5 is a left-side view thereof;

FIG. 6 is a right-side view thereof;

FIG. 7 is a front-side view thereof;

FIG. 8 is a rear-side view thereof.

FIG. 9 is a top perspective view of a tablet computer showing the new design in a second embodiment;

FIG. 10 is a bottom perspective view thereof;

FIG. 11 is a top view thereof;

FIG. 12 is a bottom view thereof;

FIG. 13 is a left-side view thereof;

FIG. 14 is a right-side view thereof;

FIG. 15 is a front-side view thereof;

FIG. 16 is a rear-side view thereof.

FIG. 17 is a top perspective view of a tablet computer showing the new design in a third embodiment;

FIG. 18 is a bottom perspective view thereof;

FIG. 19 is a top view thereof;

FIG. 20 is a bottom view thereof;

FIG. 21 is a left-side view thereof;

FIG. 22 is a right-side view thereof;

FIG. 23 is a front-side view thereof; and,

FIG. 24 is a rear-side view thereof.

The broken lines in the drawings illustrate portions of the tablet computer that form no part of the claimed design.
